COMBINED ELECTRIC LAMP AND PICTURE FRAME

Filed Oct. 3, 1932

Fig. I

Fig. II

Norbert H. Howland

INVENTOR.

UNITED STATES PATENT OFFICE

HERBERT H. HOWLAND, OF JEFFERSONVILLE, INDIANA

DESIGN FOR A COMBINED ELECTRIC LAMP AND PICTURE FRAME

Application filed October 3, 1932. Serial No. 45,197. Term of patent 14 years.

To all whom it may concern:

Be it known that I, HERBERT H. HOWLAND, a citizen of the United States, residing at Jeffersonville, in the county of Clark and the State of Indiana, have invented a new, original, and ornamental Design for a Combined Electric Lamp and Picture Frame, of which the following is a specification, reference being had to the accompanying drawing, which forms a part thereof.

Figure I is a front perspective view of a combined electric lamp and picture frame, showing my new design. The spaces in the

picture frames on the right and on the left, where the pictures are to be placed, are closed with translucent material so that the parts of the base behind them are not visible through these spaces. Figure II is a plan view of my new design.

I claim:

The ornamental design for a combined electric lamp and picture frame, substantially as shown and described.

In testimony whereof I have hereunto set my hand, this 22d day of September, 1932.

HERBERT H. HOWLAND.
